UNITED STATES PATENT OFFICE.

WILLIAM G. WOOD, OF SAN FRANCISCO, CALIFORNIA, ASSIGNOR OF ONE-HALF TO
FRANK B. McKEVITT, OF SACRAMENTO, CALIFORNIA.

DRAG-BUCKET.

1,306,873.

Specification of Letters Patent. Patented June 17, 1919.

Application filed March 23, 1917. Serial No. 156,944.

To all whom it may concern:

Be it known that I, WILLIAM G. Wood, a citizen of the United States, residing at San Francisco, in the county of San Francisco and State of California, have invented new and useful Improvements in Drag-Buckets, of which the following is a specification.

The object of the present invention is to provide, in a drag bucket, means whereby the material in the bucket can be loosened to prevent it from adhering to the walls of the bucket and to enable it to be readily discharged therefrom, which means will be automatically operated by the upward tilting of the bucket.

In the accompanying drawing, Figure 1 is a broken vertical section of one form of my invention; Fig. 2 is an end view of another form thereof; Fig. 3 is a broken side view of the latter form showing the bucket in a dumping position; Fig. 4 is a detail perspective view of parts of the mechanism.

Referring to the drawing, 1 indicates my improved drag bucket having a bale 2. The back 3 of the bucket is slidable therein, being guided by guide bars 8 and having in the centers of its top and bottom edges grooves 11 to receive said guide bars, said guide bars having at their front ends enlargements 9 forming stops for the back of the bucket. To the central portion of the rear face of the back of the bucket are secured arms 12 extending from a piston rod 13 connected to a piston 14 slidable in a cylinder 16 communicating through its side by inlet and exhaust ports 17, 18, with a steam chest 19 and an exhaust passage 21 in a slidable valve 22. Said steam chest 40 is connected at one end with a flexible pipe 23, the other end of which is connected with a source of supply of steam. Instead of steam, compressed air may be used as a pressure fluid. The slide valve is connected 45 with one end of a rod 27 which passes through an end of the steam chest and is operatively connected with one end of an arm of a bell crank lever 64 pivoted, as shown at 65, on a standard 66 extending 50 from one end of the cylinder, the outer end

of another arm thereof carrying a weight 67. When the bucket is in a horizontal position the weight 67 is in such a position relative to the pivot of the bell crank lever that its weight moves the valve to a position 55 to supply steam to the inner end of the steam cylinder. When the bucket is tilted to a vertical position, said weight acts upon the other side of the pivot of the bell crank lever, and tends to move the valve to a position 60 in which the steam is admitted to the outer end of the cylinder, thus impelling the piston to force the back 3 into the bucket. Thus the back of the bucket is moved into the bucket automatically with the turning 65 of the bucket to its vertical position, and returned to its normal position when the bucket is returned to its horizontal position. In the form of the invention shown in Figs. 2, 3, and 4, I secure on the inner 70 side of each arm of the bail a plate 49 having a cam groove 52 which engages a pin 53, carried by an arm 54, secured to and extending from, a shaft 56 having its bearings in the walls of a chamber 57, and carrying 75 a forked arm 58 which by a rod 59 actuates the slide valve as in the first described form of the invention.

I claim:

1. A drag bucket having a back slidable 80 forwardly and backwardly therein, and manually controllable means for moving the back either forwardly or backwardly in the bucket as desired and automatically operated when the bucket is tilted upwardly. 85

2. A drag bucket having a movable back and means, movable with the bucket, for pressing said back into the bucket to loosen the material therein and automatically operated when the bucket is tilted upwardly. 90

3. A drag bucket having a back slidable forwardly and backwardly therein, means, movable with the bucket, for moving the back either forwardly or backwardly in the bucket as desired, and automatically operated when the bucket is tilted upwardly, 95 and means for manually controlling said moving means from a distant point.

4. In combination with a bucket having a back movable forwardly and backwardly 100

therein, a cylinder secured on the rear portion of the bucket and a device reciprocable in said cylinder and operatively connected to the back of the bucket and automatically reciprocated when the bucket is tilted upwardly.

5. A drag bucket having a back slidable

forwardly and backwardly therein, and manually controllable means for moving the back either forwardly or backwardly in the bucket as desired and automatically operated when the bucket is moved from a horizontal to a vertical position or conversely.

W. G. WOOD.
